(57) **CLAIM**

I claim the ornamental design for a section of a flood barrier system with hook brackets for protecting building perimeter, as shown and described.

DESCRIPTION

FIG. 1 is a perspective view of a section of a flood barrier system with hook brackets for protecting building perimeter showing my new design;

FIG. 2 is a front elevational view thereof;

FIG. 3 is a rear elevational view thereof;

FIG. 4 is a right side elevational view thereof, the left side elevational view being a mirror image thereof; the broken lines depict environmental structure for illustrative purposes only and form no part of the claimed design;

FIG. 5 is a top plan view thereof; and,

FIG. 6 is a bottom plan view thereof.
